[57] **CLAIM**

The ornamental design for a tank for transporting hazardous liquids, as shown and described.

DESCRIPTION

FIG. 1 is an isometric view of a tank for transporting hazardous liquids showing our new design;

FIG. 2 is a bottom plan view thereof;

FIG. 3 is a top plan view thereof;

FIG. 4 is a side elevational view thereof, the opposite side being identical; and,

FIG. 5 is a front elevational view thereof, the rear view being identical.

FIG. 1

FIG. 2

FIG. 3

FIG. 4

FIG. 5
